UNITED STATES PATENT OFFICE.

HARVEY HUBBELL, OF BRIDGEPORT, CONNECTICUT.

PULL-SOCKET.

1,064,834.

Specification of Letters Patent.

Patented June 17, 1913.

Application filed May 6, 1912. Serial No. 695,474.

To all whom it may concern:

Be it known that I, HARVEY HUBBELL, a citizen of the United States, residing at Bridgeport, county of Fairfield, State of Connecticut, have invented an Improvement in Pull-Sockets, of which the following is a specification.

This invention relates to pull sockets for incandescent electric lamps which comprise an arrangement of the switch mechanism with relation to the insulating blocks, the current carrying brackets and the operating mechanism that will permit the use of a relatively small shell, with switch mechanism having ample current carrying capacity and arranged to operate in the horizontal plane and a direct acting relatively long operating bar between the operating mechanism and the switch mechanism, thus rendering the use of a chain within the shell unnecessary and avoiding the most frequent cause of trouble in pull sockets as ordinarily constructed.

It is essential in the present structure that the operating bar shall have relatively little swing and that its operation shall be a direct pull and practically tangential to the arc of movement of the pivotal point of the operating bar to the operating member of the switch and with these requirements in view the important feature of the present invention is to provide a special form of operating bar which may be readily connected to or disconnected from the operating mechanism so as to permit reversal of the socket or renewals, repairs, or other changes without interfering in any way with the cap, shell or mechanism within the shell, and which will effectually insulate the switch mechanism from the operating mechanism independently of any special construction or arrangement of either the switch mechanism or the operating mechanism.

With these and other objects in view, I have devised the novel insulating operating bar for pull sockets, which I will now describe referring to the accompanying drawing forming a part of this specification and using reference characters to indicate the several parts.

Figure 1 is an elevation of a pull socket partly broken away to show the arrangement of the switch mechanism with relation to the operating mechanism; Fig. 2, a

and my novel operating bar detached; Fig. 3, an edge view corresponding therewith partly in section on the line indicated by 3 in Fig. 2, looking in the direction of the arrow; Fig. 4, an inverted plan view of the operating bar; Fig. 5, an edge view partly in section illustrating a variant form of the invention; and Fig. 6 is an inverted plan view corresponding with Fig. 5.

10 denotes the socket shell, 11 the cap, 12 the insulating lining, 13 the screw shell, 14 and 15 the insulating blocks, 16 one of the current carrying brackets by which the insulating blocks are connected, 17 the switch mechanism, 18 an operating member therefor, 19 the operating lever to which a pendant 20 is connected, 21 a hub carried by a bracket 22 which is rigidly secured to the insulating blocks and 23 a bracket to which the operating lever is pivoted and which is detachably secured to the hub.

It is not considered necessary for the purpose of this specification to describe the above parts more in detail as specifically they form no portion of the present invention and the novel parts, improvements and combinations are described and claimed in other applications in Letters Patent.

My novel insulating bar consists essentially of two parts indicated respectively by 24 and 25 which are effectually insulated from each other, as in 26. Part 24 is provided at its inner end with a slot 27 which is adapted to be engaged by a T-shaped lug 28 upon switch operating member 18. The slot and the head of the lug normally lie obliquely to each other, as clearly shown in Fig. 2, so that the bar may be readily connected to the operating member by swinging the bar laterally until the slot 27 and the head of the lug are in alinement and then passing one end of the lug through the slot and dropping the bar down to place with the neck of the stud in the slot. When once attached the bar cannot be detached without again swinging it laterally to place the lug and slot in alinement which can only be done when the bar is detached from the operating lever. The outer end of part 25 is detachably connected to the operating lever in any convenient manner. In the present instance I have shown part 25 as provided with a slot 29 which is adapted to receive a hook 30 on the operating lever. At the inner end of part 25 is a slot 31

which receives a plate of insulating material and on opposite sides of said part are placed other plates of insulating material (all indicated by 26), the parts being secured together by rivets if preferred or, as shown in the drawing, by lugs 32 formed integral with part 24, which pass through the plates of insulating material and are headed down upon the under side.

10 The form illustrated in Figs. 5 and 6 differs in that part 25 has a swivel engagement, as at 33, with a plate 34 which is connected to part 24 but insulated therefrom in the same manner that the parts of the 15 bar are connected and insulated in the other form.

Having thus described my invention, I claim:

1. In a pull socket, the combination with 20 a switch operating member having a T-shaped lug, of an insulating operating bar having a slot normally lying obliquely to said lug whereby the parts are detachably connected and an operating lever to which

the other end of the bar is detachably connected. 25

2. In a pull socket, the combination with a switch operating member and a switch operating lever, of a two-part operating bar, one of said parts having a slot, insulation in said slot and on opposite sides of the part and lugs passing through the insulation by which the parts are secured together. 30

3. An operating bar of the character described comprising two members, one of which is provided with a slot, insulation in said slot and on opposite sides of said member, and lugs integral with the other member and passing through the insulation by which the parts are rigidly secured together. 35

In testimony whereof I affix my signature in presence of two witnesses.

HARVEY HUBBELL.
